(57) **CLAIM**

The ornamental design for golf swing training pivot aide, as shown and described above.

DESCRIPTION

FIG. 1 is a perspective view of an embodiment of the pivot aide;

FIG. 2 is a top view of an embodiment of the pivot aide;

FIG. 3 is a bottom view of an embodiment of the pivot aide;

FIG. 4 is a left side view of an embodiment of the pivot aide;

FIG. 5 is a right side view of an embodiment of the pivot aide;

FIG. 6 is a front view of an embodiment of the pivot aide;

FIG. 7 is a rear view of an embodiment of the pivot aide; and,

FIG. 8 is a perspective view of an embodiment shown in use of the golf swing training pivot aide.

The broken lines showing in the attached drawings are for illustrative purposes only and form no part of the claimed design.
